UNITED STATES PATENT OFFICE.

FRANKLIN A. LONG, OF EUREKA, MONTANA.

HYDRAULIC STUMP-PULLER.

1,258,691.

Specification of Letters Patent. Patented Mar. 12, 1918.

Application filed June 26, 1917. Serial No. 177,004.

To all whom it may concern:

Be it known that I, FRANKLIN A. LONG, a citizen of the United States, residing at Eureka, in the county of Flat Head and State of Montana, have invented certain new and useful Improvements in Hydraulic Stump-Pullers, of which the following is a specification.

My invention relates to improvements in hydraulic stump pullers, and the broad object thereof is the provision of a portable and very powerful contrivance of practical design which embodies novel features of construction, and a new and advantageous combination and arrangement of its essential elements.

Generally speaking, the complete apparatus includes a vehicle consisting of a frame or platform supported on skids, a horizontally disposed hydraulic cylinder with its piston and rod mounted on the platform or frame of the vehicle, a trackway on the platform at one end of the cylinder, a carriage adapted to travel on the trackway and connected to the piston rod, a rotatable cable drum or reel mounted on the carriage, a cable for the drum adapted to have one end secured to the stump to be pulled, a cable drum or reel mounted on the platform at the opposite end of the cylinder and having a cable adapted to be fastened to a tree or other anchoring means or object, and means for supplying hydraulic power to the cylinder.

The invention further includes minor features to be pointed out in the following specification wherein the details of construction will be fully described in connection with the accompanying drawings which illustrate a practical mechanism embodying the principles of the invention, and in which, Figure 1 is a severed top plan view of the complete puller.

Fig. 2 is a side elevation thereof showing the method of using the same.

Fig. 3 is an end view taken from the right of Figs. 1 and 2.

Referring more specifically to the drawings in which like reference characters indicate like parts in the several views, the numeral 1 designates the platform of a vehicle preferably supported on skids or runners 2 to render the contrivance portable. A hydraulic cylinder 3 mounted on blocks 4 se-

cured to the platform extends longitudinally of the platform, the piston rod 5 thereof having its free end connected to a carriage 6 which carriage is supported upon a pair of rollers 7 and adapted to travel lengthwise of the platform in alinement with the piston 60 and upon tracks 8. The frame of the carriage 6 has rotatably mounted thereon a cable drum or reel 9 provided with a crank handle 10 and ratchet wheels 11 and pawls 12 adapted to lock the drum to prevent reverse rotation thereof. Upon the opposite end of the platform 1 and adjacent one end of the hydraulic cylinder is mounted by means of a bracket 13 a cable drum or reel 14 having a crank handle 15 and ratchet 70 wheels 16 and pawls 17.

A fluid supply reservoir 18 has pipe connection 19 with a hydraulic pump 20 driven from any suitable source of power such as a gasoline engine (not shown) through the medium of a drive wheel 21 and power belt 22, said pump having piping 23 provided with a valve 24 to deliver fluid from the reservoir under pressure to either end of the hydraulic cylinder. To prevent blowing 80 out of the cylinder heads bypass pipes 25 having valves 25' connect the piping 23 with the opposite end portions of the cylinder so that the pressure will bypass therethrough and back to the pump when the limit of stroke of the piston is reached.

In actual use, cables 9' and 14' are intended to have their free ends fastened securely to a stump and an anchoring tree or other anchoring object, respectively, and with the piston rod 5 fully extended any slack in the cables taken up on the drums 9 and 14. Power is then applied as indicated.

In order to properly direct the stump pulling cable 9' to maintain the same in alinement with the piston so as to avoid any tendency of side stress or strain when tension is exerted on the cable, the cable is passed through a guide aperture 24 in the frame of the carriage 6 and on between opposed 100 sheaves 25 supported upon extended brackets 26.

Having described my invention, I claim:

1. In a stump puller, the combination of a portable support, tracks on the support, 105 a carriage adapted to travel on the tracks, a rotatable cable drum carried by the carriage, an additional cable drum mounted

on the support, a power cylinder mounted on the support, a piston and rod for the cylinder the outer end of the rod being connected to said carriage, and means for driving said piston.

2. In a stump puller, the combination of a portable support, tracks on the support, a carriage adapted to travel on the tracks, a rotatable cable drum carried by the carriage, 10 a cable, a guide on the carriage for the cable, extended opposed sheaves supported by brackets secured to the support and adapted to engage said cable, means for anchoring the support, a power cylinder mounted on the support, a piston and rod for the cylinder the outer end of the rod having connection with said carriage, and means for driving said piston.

3. In a stump puller, the combination of a portable support, tracks on the support, 20 a carriage adapted to travel on the tracks, a rotatable cable drum carried by the carriage, a cable, a guide on the carriage for the cable, extended opposed sheaves supported by brackets secured to the support and adapted 25 to engage said cable, anchoring means for the support, a hydraulic cylinder mounted on the support, a piston and rod for the cylinder the outer end of the rod having connection with said carriage, a fluid supply reservoir, a hydraulic pump adapted to supply 30 hydraulic power from the reservoir to the cylinder, and means for driving the pump.

In testimony whereof I affix my signature.

FRANKLIN A. LONG.
